ARTIFICIAL RESPIRATOR

Inventor: Thomas C. Huxley, III

Application, October 24, 1946, Serial No. 705,438

16 Claims. (Cl. 128—30)

1 This invention relates to new and useful improvements in artificial respirators.

Objects and advantages of the invention will be set forth in part hereinafter and in part will be obvious herefrom; or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings:

Figure 1 is a view in perspective of a preferred form of apparatus embodying features of the present invention in place on a patient;

Figure 2 is a view in longitudinal section of the apparatus and patient's body along the line of the spinal column showing schematically the position of the ribs, diaphragm, viscera and body wall in the rest stage of respiration.

Figure 3 is a view similar to Figure 2 showing the apparatus under partial evacuation, simulating the inspiration phase of respiration;

Figure 4 is a view of the apparatus in side elevation shown from the patient's left;

Figure 5 is a bottom plan view of the apparatus; and

Figure 6 is a view in end elevation viewed from the abdominal end of the apparatus showing the fitting means extended and contracted.

Referring to the drawings in detail and particularly to Figure 1, a shell shaped casing 8, constructed of a lightweight material, sufficiently rigid to resist deformation under moderate suction, such as Plexiglas, fits over, rests upon and encloses the frontal position only, of the patient's chest, said casing 8 being provided around its edge, which makes contact with the patient's body, with sealing means 10, made of a soft, yielding air impervious material such as foam rubber, which may be covered with a thin, resiliently yieldable material such as rubber sheeting. The sealing means 10, extending beyond each abdominal end of the casing edge, contacts the body to form cubical abutments 12 thereto, the sealing means 10 forming a substantially air-tight seal, when the casing 8 rests upon the patient's body. Closure means, consisting in the preferred embodiment of the invention of a resiliently yieldable thin rubber sheet 14 are provided, said sheet 14

2 being sealed to the lower or abdominal edge 16 of the casing 8 and to the abutments 12 thereto, the edge 16 not being in contact with the patient's body but being a convex arch. Slight tension in the upper part of the sheet 14 is provided by its seal with edge 16 but slight looseness or slack is provided in the lower portion of the sheet 14 with the result that its loose, lower portion makes substantial contact with the patient's upper abdomen.

A member 18, apertured to receive a vertically extending rod member 20, which is secured upon a base 22 is provided on either side of the lower end of the casing 8, said member 18 being apertured to receive transversely extending variable position set screws 24, which make contact with rod member 20, thereby permitting regulation of the supporting length of rod member 20.

A clevis 26, apertured to receive rod member 20 fits over and pivots upon member 18, said clevis 26 carrying a transversely extending rod member 28, fixed at one end in the clevis 26 and being threaded received at its other end by a turnbuckle 30. Thus the width of the casing 8 is adjustable through approximately three to five inches, as varying chest sizes of patients may require.

A suction duct 32 enters the casing 8 at 34 and is connected to a bellows or other suction device, not shown, so that when moderate suction of three to five inches of water is applied to the chest and upper abdomen, the casing 8 having a substantially air-tight seal with the body by virtue of edge seal 10 and rubber sheet 14, a partial vacuum will be created inside casing 8 which will react upon the body wall, thorax, diaphragm, abdominal cavity and viscera of the patient as shown in Fig. 2 and Fig. 3 and more fully described hereinafter so as to simulate the rest to inspiration phase of breathing. A return to normal pressure inside casing 8 simulates the expiration to rest phase of respiration.

In the operation of the above device, the casing 8 is placed on the patient's chest as shown in Fig. 1, vertically extending rod members 20 and set screws 24 being so adjusted that much of the weight of the apparatus will rest upon the bed and not upon the patient, while the width of the casing 8 is adjusted to the patient's chest size by adjustment of spacing means consisting of the turnbuckle 30 and rod members 28.

Sealing means 10 and the resiliently yieldable rubber sheet 14 provide a substantially air-tight seal between casing 8 and the body of the patient and when moderate suction of three to

five inches of water is applied through suction duct 32 to the casing 8 by means of a bellows or other suction pump device, a partial vacuum is produced. Fig. 2 shows a longitudinal section of the body taken along the line of the backbone with the apparatus in place but not evacuated. The thorax A is separated from the abdominal cavity B by the diaphragm C which extends convexly upward like a dome into the thorax when in the expiration phase of respiration as schematically shown in Fig. 2. Fig. 3 shows schematically what happens during inspiration as induced by the action of the apparatus. The ribs D are pulled to a position approximately at right angles to the backbone by the action of the intercostal muscles, the thorax expanding as the body wall E is displaced upwardly into the partially evacuated casing 8. The diaphragm C flattens, displacing the liver F and the stomach G downwardly with this flattening of the diaphragm being further aided by displacement of body wall E upwardly into the case 8, which expands the abdominal cavity A. Comparison of the Figs. 2 and 3 will also show the change in positioning of the rubber sheet 14 when the case 8 is partially evacuated. Alternation between partial evacuation and normal pressure of the air within casing 8 at the rate of approximately sixteen times per minute for an adult patient will successfully simulate normal respiration.

The lightweight apparatus shown in the preferred embodiment of the invention is so sealed to the frontal portion only of the patient's torso and is so supported at its lower end that much of its weight rests upon the bed so that skin irritation and discomfort to the patient is minimized when the apparatus is worn over long periods of time. The apparatus is readily adjustable to different chest sizes and permits considerable necessary motion to the patient, thus facilitating his treatment as by manipulation. The sturdy, inexpensive, lightweight construction, readily adjustable to various chest sizes, minimizing the patient's discomfort presents marked improvement over the cumbersome expensive respirators now in use and marks a considerable improvement in the treatment of patients suffering from paralysis of the respiratory muscles.

The invention in its broader aspects is not limited to the specific mechanisms shown and described but departures may be made therefrom within the scope of the accompanying claims without departing from the principles of the invention and without sacrificing its chief advantages.

What I claim is:

1. In an apparatus for producing artificial respiration, the combination of a casing to fit over, rest upon and enclose the frontal portion only of the patient's chest and upper abdomen, said casing having a suction duct fitted thereto and being sufficiently rigid to resist deformation under moderate suction applied through said duct to the chest and upper abdomen; means for supporting said casing at its abdominal end, relieving the patient of much of the weight of the apparatus; means at the abdominal end of said casing to adjust its width to different chest sizes; means for sealing said casing to the chest at the sides and adjacent to the clavicles; closure means at the lower end of said casing, adapted to make substantial contact with the abdomen; whereby the thorax and abdominal cavity are

expanded and the diaphragm is downwardly displaced, causing inhalation when said moderate suction is applied to the chest and upper abdomen through said duct.

5 2. In an apparatus for producing artificial respiration, the combination of a casing to fit over, rest upon and enclose the frontal portion only of the patient's chest and upper abdomen, said casing having a suction duct fitted thereto and being sufficiently rigid to resist deformation under moderate suction applied through said duct to the chest and upper abdomen; a member on either side of the lower end of said casing, having an aperture therein to receive a vertically extending rod member which is secured upon a base, said member having means for securing said rod member in various positions whereby said casing may be positioned so that much of its weight is carried by said rod member and bears upon the bed, rather than upon the patient's body; means at the abdominal end of said casing to adjust its width to different chest sizes; means for sealing said casing to the chest at the sides and adjacent to the clavicles; 20 closure means at the lower end of said casing, adapted to make substantial contact with the abdomen; whereby the thorax and abdominal cavity are expanded and the diaphragm is displaced, causing inhalation when said moderate suction is applied to the chest and upper abdomen through said duct.

3. In an apparatus for producing artificial respiration, the combination of a casing to fit over, rest upon and enclose the frontal portion only of the patient's chest and upper abdomen, said casing having a suction duct fitted thereto and being sufficiently rigid to resist deformation under moderate suction applied through said duct to the chest and upper abdomen; means for supporting said casing at its abdominal end, relieving the patient of much of the weight of the apparatus; a clevis, having an aperture therein to receive a vertically extending rod member fitted over a member on either side of the lower end of said casing, said clevis carrying a transversely extending rod member, fixed at one end in said clevis, forming a portion of a turnbuckle whereby the width of said casing may be varied to fit different chest sizes; means for sealing said casing to the 45 chest at the sides and adjacent to the clavicles; closure means at the lower end of said casing, adapted to make substantial contact with the abdomen; whereby the thorax and abdominal cavity are expanded and the diaphragm is displaced, 50 causing inhalation when said moderate suction is applied to the chest and upper abdomen through said duct.

4. In an apparatus for producing artificial respiration, the combination of a casing to fit over, rest upon and enclose the frontal portion only of the patient's chest and upper abdomen, said casing having a suction duct fitted thereto and being sufficiently rigid to resist deformation under moderate suction applied through said duct to the chest and upper abdomen; means for supporting said casing at its abdominal end, relieving the patient of much of the weight of the apparatus; means at the abdominal end of said casing to adjust its width to different chest sizes; sealing means of a soft, yielding substance covered with thin sheet material to render it air impervious, said sealing means being fastened to the edge of said casing which contacts the patient's body and extending beyond each abdominal end of the edge of said casing contacting

the body, said sealing means forming a substantially air-tight seal when said casing rests upon the patient's body; closure means at the lower end of said casing, adapted to make substantial contact with the abdomen; whereby the thorax and abdominal cavity are expanded and the diaphragm is displaced, causing inhalation when said moderate suction is applied to the chest and upper abdomen through said duct.

5. In an apparatus for producing artificial respiration, the combination of a casing to fit over, rest upon and enclose the frontal portion only of the patient's chest and upper abdomen, said casing having a suction duct fitted thereto and being sufficiently rigid to resist deformation under moderate suction applied through said duct to the chest and upper abdomen; means for supporting said casing at its abdominal end, relieving the patient of much of the weight of the apparatus; means at the abdominal end of said casing to adjust its width to different chest sizes; means for sealing said casing to the chest at the sides and adjacent to the clavicles; a resiliently yieldable, thin rubber-like sheet, sealed to the lower or abdominal edge of said casing which arches convexly away from the patient's body and to block like abutments, where the ends of said sealing means between the body and the edge of said casing extend beyond lower edges of said casing, slight tension being provided in the upper part of said sheet by its seal with the edge of the abdominal end of said casing and slight looseness or slack being provided in the lower portion of said sheet by its seal with the edge of the abdominal end of said casing and with said block like abutments, whereby the loose, lower portion makes substantial contact with the patient's abdomen; the thorax and abdominal cavity being expanded and the diaphragm displaced, thus causing inhalation when said moderate suction is applied to the chest and upper abdomen through said duct.

6. In an apparatus for producing artificial respiration, the combination of a casing to fit over, rest upon and enclose the frontal portion only of the patient's chest and upper abdomen, said casing having a suction duct fitted thereto and being sufficiently rigid to resist deformation under moderate suction applied through said duct to the chest and upper abdomen; a member on either side of the lower end of said casing, having an aperture therein to receive a vertically extending rod member which is secured upon a base, said member having means for securing said rod member in various positions whereby said casing may be positioned so that much of its weight is carried by said rod member and bears upon the bed, rather than upon the patient's body; a clevis, having an aperture therein to receive a vertically extending rod member, fitted over a member on either side of the lower end of said casing, said clevis carrying a transversely extending rod member, fixed at one end in said clevis, forming a portion of a turnbuckle whereby the width of said casing may be varied to fit different chest sizes; means for sealing said casing to the chest at the sides and adjacent to the clavicles; closure means at the lower end of said casing, adapted to make substantial contact with the abdomen; whereby the thorax and abdominal cavity are expanded and the diaphragm is displaced, causing inhalation when said moderate suction is applied to the chest and upper abdomen through said duct.

7. In an apparatus for producing artificial

respiration, the combination of a casing to fit over, rest upon and enclose the frontal portion only of the patient's chest and upper abdomen, said casing having a suction duct fitted thereto and being sufficiently rigid to resist deformation under moderate suction applied through said duct to the chest and upper abdomen; a member on either side of the lower end of said casing, having an aperture therein to receive a vertically extending rod member which is secured upon a base, said member having means for securing said rod in various positions whereby said casing may be positioned so that much of its weight is carried by said rod member and bears upon the bed, rather than upon the patient's body; a clevis, having an aperture therein to receive a vertically extending rod member, fitted over a member on either side of the lower end of said casing, said clevis carrying a transversely extending rod member, fixed at one end in said clevis, forming a portion of a turnbuckle whereby the width of said casing may be varied to fit different chest sizes; sealing means of a soft, yielding substance covered with thin sheet material to render it air impervious, said sealing means being fastened to the edge of said casing which contacts the patient's body and extending beyond each abdominal end of the edge of said casing contacting the body, said sealing means forming a substantially air-tight seal when said casing rests upon the patient's body; closure means at the lower end of said casing, adapted to make substantial contact with the abdomen; whereby the thorax and abdominal cavity are expanded and the diaphragm is displaced, causing inhalation when said moderate suction is applied to the chest and upper abdomen through said duct.

8. In an apparatus for producing artificial respiration, the combination of a casing to fit over, rest upon and enclose the frontal portion only of the patient's chest and upper abdomen, said casing having a suction duct fitted thereto and being sufficiently rigid to resist deformation under moderate suction applied through said duct to the chest and upper abdomen; means for supporting said casing at its abdominal end, relieving the patient of much of the weight of the apparatus; a clevis, having an aperture therein to receive a vertically extending rod member, fitted over a member on either side of the lower end of said casing, said clevis carrying a transversely extending rod member, fixed at one end in said clevis, forming a portion of a turnbuckle whereby the width of said casing may be varied to fit different chest sizes; sealing means of a soft, yielding substance covered with thin sheet material to render it air impervious, said sealing means being fastened to the edge of said casing which contacts the patient's body and extending beyond each abdominal end of the edge of said casing contacting the body, said sealing means forming a substantially air-tight seal when said casing rests upon the patient's body; closure means at the lower end of said casing, adapted to make substantial contact with the abdomen; whereby the thorax and abdominal cavity are expanded and the diaphragm is displaced, causing inhalation when said moderate suction is applied to the chest and upper abdomen through said duct.

9. In an apparatus for producing artificial respiration, the combination of a casing to fit over, rest upon and enclose the frontal portion only of the patient's chest and upper abdomen, said casing having a suction duct fitted thereto and being sufficiently rigid to resist deformation

under moderate suction applied through said duct to the chest and upper abdomen; means for supporting said casing at its abdominal end, relieving the patient of much of the weight of the apparatus; a clevis, having an aperture therein to receive a vertically extending rod member, fitting over a member on either side of the lower end of said casing, said clevis carrying a transversely extending rod member, fixed at one end in said clevis, forming a portion of a turnbuckle whereby the width of said casing may be varied to fit different chest sizes; sealing means of a soft, yielding substance covered with thin sheet material to render it air impervious, said sealing means being fastened to the edge of said casing which contacts the patient's body and extending beyond each abdominal end of the edge of said casing contacting the body, said sealing means forming a substantially air-tight seal when said casing rests upon the patient's body; a resiliently yieldable, thin rubber-like sheet, sealed to the lower or abdominal edge of said casing which arches convexly away from the patient's body and to block like abutments, where the ends of said sealing means between the body and the edge of said casing extend beyond lower edges of said casing, slight tension being provided in the upper part of said sheet by its seal with the edge of the abdominal end of said casing and slight looseness or slack being provided in the lower portion of said sheet by its seal when the edge of the abdominal end of said casing and with said block like abutments, whereby the loose, lower portion makes substantial contact with the patient's abdomen; the thorax and abdominal cavity being expanded and the diaphragm displaced, thus causing inhalation when said moderate suction is applied to the chest and upper abdomen through said duct.

10. In an apparatus for producing artificial respiration, the combination of a casing to fit over, rest upon and enclose the frontal portion only of the patient's chest and upper abdomen, said casing having a suction duct fitted thereto and being sufficiently rigid to resist deformation under moderate suction applied through said duct to the chest and upper abdomen; means for supporting said casing at its abdominal end, relieving the patient of much of the weight of the apparatus; means at the abdominal end of said casing to adjust its width to different chest sizes; sealing means of a soft, yielding substance covered with thin sheet material to render it air impervious, said sealing means being fastened to the edge of said casing which contacts the patient's body and extending beyond each abdominal end of the edge of said casing contacting the body, said sealing means forming a substantially air-tight seal when said casing rests upon the patient's body; a resiliently yieldable, thin rubber-like sheet, sealed to the lower or abdominal edge of said casing which arches convexly away from the patient's body and to block like abutments, where the ends of said sealing means between the body and the edge of said casing extend beyond the lower edges of said casing, slight tension being provided in the upper part of said sheet by its seal with the edge of the abdominal end of said casing and slight looseness or slack being provided in the lower portion of said sheet by its seal with the edge of the abdominal end of said casing and with said block like abutments, whereby the loose, lower portion makes substantial contact with the patient's abdomen; the thorax and abdominal

cavity being expanded and the diaphragm displaced, thus causing inhalation when said moderate suction is applied to the chest and upper abdomen through said duct.

- 5 11. In an apparatus for producing artificial respiration, the combination of a casing to fit over, rest upon and enclose the frontal portion only of the patient's chest and upper abdomen, said casing having a suction duct fitted thereto
10 and being sufficiently rigid to resist deformation under moderate suction applied through said duct to the chest and upper abdomen; a member on either side of the lower end of said casing, having an aperture therein to receive a vertically
15 extending rod member which is secured upon a base, said member having means for securing said rod member in various positions whereby said casing may be positioned so that much of its weight is carried by said rod member and bears
20 upon the bed, rather than upon the patient's body; means at the abdominal end of said casing to adjust its width to different chest sizes; means for sealing said casing to the chest at the sides and adjacent to the clavicles; a resiliently yieldable, thin rubber-like sheet, sealed to the lower or abdominal edge of said casing which arches convexly away from the patient's body and to block like abutments, where the ends of said
25 sealing means between the body and the edge of
30 said casing extend beyond the lower edges of said casing, slight tension being provided in the upper part of said sheet by its seal with the edge of the abdominal end of said casing and slight looseness or slack being provided in the lower portion of said sheet by its seal with the edge of the abdominal end of said casing and with said block like abutments, whereby the loose, lower portion makes substantial contact with the patient's abdomen; the thorax and abdominal cavity being expanded and the diaphragm displaced, thus causing inhalation when said moderate suction is applied to the chest and upper abdomen through said duct.
35 12. In an apparatus for producing artificial respiration, the combination of a casing to fit over, rest upon and enclose the frontal portion only of the patient's chest and upper abdomen, said casing having a suction duct fitted thereto
40 and being sufficiently rigid to resist deformation under moderate suction applied through said duct to the chest and upper abdomen; a member on either side of the lower end of said casing, having an aperture therein to receive a vertically extending rod member which is secured upon a base, said member having means for securing said rod member in various positions whereby said casing may be positioned so that much of its weight is carried by said rod member and bears
45 upon the bed, rather than upon the patient's body; means at the abdominal end of said casing to adjust its width to different chest sizes; sealing means of a soft, yielding substance covered with thin sheet material to render it air impervious, said sealing means being fastened to the edge of said casing which contacts the patient's body and extending beyond each abdominal end of the edge of said casing contacting the body, said sealing means forming a substantially air-tight seal when said casing rests upon the patient's body; a resiliently yieldable, thin rubber-like sheet, sealed to the lower or abdominal edge of said casing which arches convexly away from the patient's body and to block like abutments, where the ends of said sealing means between the body and the edge of said casing extend beyond the

lower edges of said casing, slight tension being provided in the upper part of said sheet by its seal with the edge of the abdominal end of said casing and slight looseness or slack being provided in the lower portion of said sheet by its seal with the edge of the abdominal end of said casing and with said block like abutments, whereby the loose, lower portion makes substantial contact with the patient's abdomen; the thorax and abdominal cavity being expanded and the diaphragm displaced, thus causing inhalation when said moderate suction is applied to the chest and upper abdomen through said duct.

13. In an apparatus for producing artificial respiration, the combination of a casing to fit over, rest upon and enclose the frontal portion only of the patient's chest and upper abdomen, said casing having a suction duct fitted thereto and being sufficiently rigid to resist deformation under moderate suction applied through said duct to the chest and upper abdomen; a member on either side of the lower end of said casing, having an aperture therein to receive a vertically extending rod member which is secured upon a base, said abutment having means for securing said rod member in various positions whereby said casing may be positioned so that much of its weight is carried by said rod member and bears upon the bed, rather than upon the patient's body; means at the abdominal end of said casing to adjust its width to different chest sizes; sealing means of a soft, yielding substance covered with thin sheet material to render it air impervious, said sealing means being fastened to the edge of said casing which contacts the patient's body and extending beyond each abdominal end of the edge of said casing contacting the body, said sealing means forming a substantially air-tight seal when said casing rests upon the patient's body; closure means at the lower end of said casing, adapted to make substantial contact with the abdomen; whereby the thorax and abdominal cavity are expanded and the diaphragm is displaced, causing inhalation when said moderate suction is applied to the chest and upper abdomen through said duct.

14. In an apparatus for producing artificial respiration, the combination of a casing to fit over, rest upon and enclose the frontal portion only of the patient's chest and upper abdomen, said casing having a suction duct fitted thereto and being sufficiently rigid to resist deformation under moderate suction applied through said duct to the chest and upper abdomen; a member on either side of the lower end of said casing, having an aperture therein to receive a vertically extending rod member which is secured upon a base, said member having means for securing said rod member in various positions whereby said casing may be positioned so that much of its weight is carried by said rod member and bears upon the bed, rather than upon the patient's body; a clevis, having an aperture therein to receive a vertically extending rod member, fitting over a block like abutment on either side of the lower end of said casing, said clevis carrying a transversely extending rod member, fixed at one end in said clevis, forming a portion of a turnbuckle whereby the width of said casing

may be varied to fit different chest sizes; means for sealing said casing to the chest at the sides and adjacent to the clavicles; a resiliently yieldable, thin rubber-like sheet, sealed to the lower or abdominal edge of said casing which arches convexly away from the patient's body and to block like abutments, where the ends of said sealing means between the body and the edge of said casing extend beyond the lower edges of said casing, slight tension being provided in the upper part of said sheet by its seal with the edge of the abdominal end of said casing and slight looseness or slack being provided in the lower portion of said sheet by its seal with the edge of the abdominal end of said casing and with said block like abutments, whereby the loose, lower portion makes substantial contact with the patient's abdomen; the thorax and abdominal cavity being expanded and the diaphragm displaced, thus causing inhalation when said moderate suction is applied to the chest and upper abdomen through said duct.

15. In an apparatus for producing artificial respiration, the combination of a casing to fit over the patient's chest and upper abdomen, said casing having a suction duct fitted thereto and being sufficiently rigid to resist deformation under moderate suction applied through said duct to the chest and upper abdomen; means for supporting said casing at its abdominal end relieving the patient of much of the weight of the apparatus; closure means at the lower end of said casing, adapted to make substantial contact with the abdomen; whereby the thorax and abdominal cavity are expanded and the diaphragm is displaced, causing inhalation when said moderate suction is applied to the chest and upper abdomen through said duct.

16. In an apparatus for producing artificial respiration, the combination of a casing to fit over the patient's chest and upper abdomen, said casing having a suction duct fitted thereto and being sufficiently rigid to resist deformation under moderate suction applied through said duct to the chest and upper abdomen; means at the abdominal end of said casing to adjust its width to different chest sizes; means for sealing said casing to the chest at the sides and adjacent to the clavicles; closure means at the lower end of said casing, adapted to make substantial contact with the abdomen, said closure means comprising a thin rubber-like sheet sealed to and supported on the abdominal end of said casing; whereby the thorax and abdominal cavity are expanded and the diaphragm is displaced, causing inhalation when said moderate suction is applied to the chest and upper abdomen through said duct.
